UNITED STATES PATENT OFFICE.

EMILE SEYMOUR DREUX, OF NEW YORK, N. Y.

DESIGN FOR RIBBON.

No. 38,240.

Specification for Design.

Patented Sept. 18, 1906.

Application filed July 16, 1906. Serial No. 326,520. Term of patent 3½ years.

To all whom it may concern:

Be it known that I, EMILE SEYMOUR DREUX, a citizen of the United States, residing in the city, county, and State of New York, have invented a new, original, and ornamental Design for Ribbons, of which the following is a specification, reference being had to the accompanying drawing, forming part thereof.

The figure is a plan view of the design as applied to a ribbon or the like.

I claim—

The ornamental design for a ribbon, as shown.

EMILE SEYMOUR DREUX.
